CLAIM

The ornamental design for a storage compartment for a folding ironing board as shown and described.

DESCRIPTION

FIG. 1 is a front view of a storage compartment for a folding ironing board showing the new design.

FIG. 2 is a right side view thereof; the left side view is a mirror image of the right side view shown.

FIG. 3 is a top view thereof; and,

FIG. 4 is a bottom view thereof.

The evenly broken lines shown in the figures depict portions of the article of manufacture that form no part of the claimed design.

1 Claim, 4 Drawing Sheets
